UNITED STATES PATENT OFFICE.

HENRY L. PITMAN, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,370,360.

Specification of Letters Patent.

Patented Mar. 1, 1921.

Application filed November 19, 1918. Serial No. 263,158.

To all whom it may concern:

Be it known that I, HENRY L. PITMAN, a citizen of the United States, residing in Elizabeth, in the county of Union and State of New Jersey, have invented certain new and useful Improvements in Combined Typewriting and Computing Machines, of which the following is a specification.

This invention relates to computing machines, and is herein disclosed as applied to a combined typewriting and computing machine of the Underwood-Hanson type, wherein the numbers written by the numeral keys of the typewriter while being written are set up by means of pins on pin-bars, and after a number is completely set up in this way, it is carried into the computing wheels.

In such machines, the mechanism is somewhat complex, and the movements of parts, especially in the operation of setting up numbers, are necessarily small but extremely accurate, with the result that the machine is somewhat difficult to assemble. Moreover, adjustments may become deranged if dirt is allowed to accumulate in the bearings or between bearing points.

The present invention is more especially directed to the structure known as the transposition device, by means of which numbers, which are written on the work-sheet on the platen, which travels to the left, may be set up on the proper pin-bars beginning at the left and going toward the right. This transposition device, in some forms of the mechanism already in use, comprises arms which are adapted to thrust forwardly to a small extent the pin-bars, so that the pins thereon, which are normally out of alinement with the pin-setting bars, may be brought into alinement with said bars, with the result that any actuated bar sets up a pin on the bar which has its pins in alinement at the moment.

According to the present invention, the jacks which are usually adjacent the typewriter carriage, and selectable by a dog thereon may be caused to effect the selec-

tion by displacing the usual rods, and each rod may be directly connected to move its own pin-bar by a one-piece bell-crank, or bail in the form of a bell-crank, thus reducing the number of bearings. In other words, many parts are eliminated and all the work is done by mechanism of simpler construction. It has been the practice to connect the lower ends of these rods to the horizontal arms of bell-cranks, and then to connect the pendent arms of said bell-cranks to a complex transposition device. According to the present invention, however, there may be used for connecting said rods to the pin-bars (or computation-bars) no more than a single set of bell-cranks, and these may not only change the up-and-down motions of the rods to the back-and-forth motions of the pin-bars, but may also constitute a transposition device, since one set of bell-crank-arms has the reverse denominational order from the other set of bell-crank-arms. To effect this reversal, the bell-cranks are mainly made in the form of graduated bails, and the bails are so formed and nested as to give the desired result. One of the main features of the invention therefore is the provision of bell-cranks forming in themselves a transposition device between the rods and the pin-bars.

The set or system of computation-bars is usually of substantially greater width than the set of rods or denominational devices, the latter being usually arranged at letter-space intervals; and one of the features of the invention is that the bail-like bell-cranks are so contrived that one set of arms, for connection to the rods, is of substantially less width than the other set of arms, for connection with the computation-bars. Thus there are three advantages gained, first, the connection of the rods to the computation-bars by a simple set of bell-cranks; second, the bell-cranks constituting in themselves a transposition device, and, third, the bell-cranks compensating for the difference in width between the set of rods and the set of computation-bars. A fourth sid-

vantage is gained in that the bell-cranks are simply and readily mounted upon a support in a manner to be assembled as a unit for attachment to and detachment from the machine. Since these bails or bell-cranks may all be journaled on a common shaft and held in place by a comb, the mechanism is easily assembled and may be readily made out of stamped metal parts, thus rendering it possible to build a strong and yet inexpensive device.

Other features and advantages will hereinafter appear.

In the accompanying drawings, 15 Figure 1 is a sectional side view of an Underwood-Hanson bookkeeping machine, showing the present invention as applied thereto.

Fig. 2 is a perspective view of the transposition device detached from most of the machine.

Fig. 3 is a perspective view of a bail or bell-crank forming part of the transposition device.

25 Fig. 4 is a sectional front view of the bell-cranks or bails.

In the usual Underwood-Hanson bookkeeping machine, the numeral keys 1 and alphabet keys 2, when depressed, carry down 30 their key-levers 3, so as to rock bell-cranks 4 to carry type-bars 5 upwardly and rearwardly against the platen 6, so that types 7 thereon will print against the front side of the platen. The typewriter carriage travels on front and rear rails 8 and 9, and is drawn along by a spring barrel, not shown.

In order to control the travel of the carriage, there is provided the usual rack bar 40 10 meshing with a pinion 11 connected to the escapement wheel 12, said wheel being adapted to be engaged alternately by the dogs 13 in the usual manner when the universal bar 14 is struck by the usual heels 15 45 on the type-bars. Whenever a numeral key is depressed, it carries down its pendant 17 to strike a rock arm 18 on a rock shaft 19, so as to actuate a pin-setting linkage 20 to which the rock shaft is connected. One 50 form of mechanism showing this and some other features is shown in the application of Frederick A. Hart, Serial No. 783,258, filed August 6, 1913 (now Patent No. 1,287,301, dated December 10, 1918). The pin-setting linkages 20 are adapted to set up on 55 pin-bars 21 pins 22 in an order determined by the typewriter carriage, the pins set up depending on the numeral key 1, which is actuated at any moment. Normally the 60 pins 22 are in the position shown in Fig. 1 where they are seen out of alignment with their linkages 20. In the adding zone, however, the pin-bars 21 are moved forward *seriatim* to bring their pins into setting position. To effect this, there is provided the

usual denomination-selector 23 adjustably mounted on the typewriter carriage, and adapted to be carried along thereby under the front ends of jacks 24, so as to depress the rear ends of said jacks and carry down 70 the rods or wires 25, there being one rod for each jack. Between the wires or rods 25 and the pin-setting bars 21, the connections form part of a transposition device which includes a series of bell-crank arms 26, each 75 having a hook 27 into which the lower end of its wire 25 is adapted to be inserted and to rest, so that when the wire 25 is depressed, the arm 26 will be depressed and rock forwardly the depending arm 28 fast to the arm 26, said arm 28 having a hook 29 which may be like the hook 27, and which is adapted to lie against the pin 30 at the rear end of its pin-bar 21. The bell-crank arms 26 and 28 are connected by bail members 31 integral therewith, so that the two arms 26 and 28 form a bell-crank, as seen in Fig. 3. The arms 26 are journaled upon a shaft 32, which is in turn mounted or journaled on upright arms 33 and 34 forming a mounting for the 90 shaft. In order to hold the shaft 32 in place, one end may enter a socket 35 in the arm 34, and the other end may rest in the open fork 36 at the upper end of the arm 33 and be held therein by a spring latch 37 95 adapted to engage a reduced portion 38 of the shaft.

In order to hold the arms 28 properly spaced so that they lie adjacent their own pin-bars 21, the uprights 33 and 34 support 100 a comb 39 in the form of a U-shaped piece of metal having its bent-over ears 40 held by screws 41 to the uprights 33 and 34, and serving to steady the uprights. In assembling the mechanism, it is customary to lay 105 the comb on a table and insert in the proper spaces therein the proper arms 28 and then to pass the shaft 32 through the openings 42 in the arms 28 and 26, in this way avoiding any difficulties of assembling 110 awkwardly-shaped parts, such as the arms projecting from the bail parts 31. In order to hold the arms 28 in place in the comb 39, a turned-down bar 43 may have ears 44 which are adapted to be held by screws 45 to the 115 comb 39, the bar extending across the space occupied by the various arms 28 and serving to limit their throw. Since the throw of the arms 28 in the direction of the bar 43 may be varied considerably without displacing other parts, no means for adjusting the bar 43 are shown. The arms 28, however, when swung forwardly, under the influence of the selector 23, must bring the pins 22 on their bars to setting position, and therefore the throw 120 of the arms 28 forwardly must be gauged accurately. In order to enable this gauging to be done in a specially built machine, there is provided on the comb 39 an adjusting bar 46 held thereto by screws 47 and provided 125

with adjustable screws 48, against which the arms 28 are adapted to strike when any one has brought its bar 21 to pin-setting position. In order to prevent the screws 48 from loosening, they may be provided with locking screws 49.

- In order to enable the transposition mechanism, the main features of which have just been described, to be applied to machines of 10 the kind now in use, the uprights 33 and 34 are formed as bent-over U-shaped extensions by a stamped-out plate 50, said plate being supported on rods 51, to which it is screwed by the screws 52 passing through 15 openings 53 at the lower end of the plate 50. These rods extend rearwardly from a plate 54 which is curved to fit them, and to which they are held by screws 55,—the plate 54 being fast to the usual bracket 56.
- 20 As will clearly be seen from Fig. 2, the arms 26 and 28, together with their bail parts 31, form two overlapping nests of bails standing clear of each other, the two sets of bails being substantially at right 25 angles to each other. Owing to the fact that the bails 31 are of considerable length, the openings 42 in them give them a good bearing on the shaft 32. One of the arms 26, namely, the center one, forms with its 30 dependent arm 28 a bell-crank without any intervening bail, and to give this arm the desired bearing, it may have a hub 57 by which it is journaled on the shaft 32. As 35 will be seen from Fig. 2, half the bails 31 are above the hub 57 and the other half are in front of said hub.

When any jack is raised by the selector 23 to press its rack bar 21 forward, it does so against the tension of a spring 58 which 40 normally draws a detent arm 59, made of doubled over sheet metal and having a roller 60 between them, against an elbow 61 of the pin-bar 21. Thus, the spring 58 holds the pin-bar in its rearward position. The 45 detent arm 59 may comprise an opening 60^a, thus enabling each of its metal sides to have a point 61^a seated in a hollow or opening 62 of a cross-bar 63, so that the detent arm turns freely on its point. In order to keep 50 the detent arms properly spaced from each other, the bar 63 is provided with spaced collars 65. This bar 63 is conveniently formed from a solid shaft having the spaces between the collars 65 turned down to form 55 grooves into which extend detent arms 59, and then being channeled lengthwise to form the opening 62.

In order to compute the numbers set up on the pin-bars, the operative may draw on 60 a handle 66 to actuate in the usual way the general operator 67, so that its cross-bar 68 will strike the abutments of the depressed pins, thereby driving the pin-bars 21 forward so that each turns its computing wheel 65 68^a. On the return stroke, the usual carry-

over mechanism 69 effects carry-overs, and the pins are restored in the usual manner by the pin-restoring plate 70. The bar 63 may be supported on arms 71 fast to the upper part of a comb 72, said comb in turn being 70 fast to the top of a bottom comb 73 which is held by screws 74 on the front ends of the rods 51, there being an opening between the combs 72 and 73.

Variations may be resorted to within the 75 scope of the invention, and portions of the improvements may be used without others.

Having thus described my invention, I claim:

1. The combination with a traveling selector and denominational bars, of an array of jacks moved *seriatim* by said selector, a transposition device between said bars and said jacks, said device comprising a set of nested bails, a single shaft for said bails, an 80 arm whereby each bail moves its bar, and stops for limiting the throw of the arms to position the bars.

2. The combination with a traveling selector and denominational bars, of pins set 90 table on said bars, pin-setting links normally out of alinement with said pins, an array of jacks adapted to be moved by said selector, a set of nested bails forming a transposition device, a single shaft on which 95 said bails are journaled, an arm on each bail for its jack, and an arm on each bail for its denominational bar to shift the bar to carry its pins into alinement.

3. The combination with a traveling selector and denominational bars, of pins set 100 table on said bars, pin-setting links normally out of alinement with said pins, an array of jacks adapted to be moved by said selector, a set of nested bails forming a 105 transposition device, a single shaft on which said bails are journaled, an arm on each bail for its jack, an arm on each bail for its denominational bar to shift the bar to carry its pins into alinement, and stops for arresting the throw of the arms when the pins are 110 in alinement.

4. The combination with a traveling selector and denominational bars, of pins set 115 table on said bars, pin-setting links normally out of alinement with said pins, an array of jacks adapted to be moved by said selector, a set of nested bails forming a transposition device, a single shaft on which 120 said bails are journaled, an arm on each bail for its jack, an arm on each bail for its denominational bar to shift the bar to carry its pins into alinement, stops for arresting the throw of the arms when the pins are in alinement, and a spring for each denominational bar normally holding it against its arm.

5. The combination with a traveling selector and denominational bars, of pins set 125 table on said bars, pin-setting links nor- 130

1 mally out of alinement with said pins, an array of jacks adapted to be moved by said selector, a set of nested bails forming a transposition device, a single shaft on which 5 said bails are journaled, an arm on each bail for its jack, an arm on each bail for its denominational bar to shift the bar to carry its pins into alinement, a hooked end on the bail arm, and a pin on each denominational 10 bar normally resting in its hooked end and by which it is shifted to bring the settable pins into alinement.

6. A transposition device comprising a frame having ends, a shaft having one end 15 seated in the frame, the other end being seated in an opening at the other end of the frame, means for detachably holding the shaft in the opening, bails having transposition arms journaled on the shaft, and a 20 spacing member for engaging one set of arms adapted to be fastened to said frame.

7. A transposition device comprising a frame having ends, a shaft having one end seated in the frame, the other end being 25 seated in an opening at the other end of the frame, means for detachably holding the shaft in the opening, bails having transposition arms journaled on the shaft, a comb member for engaging one set of arms adapted 30 to be fastened to said frame, and stops in said comb member adapted to limit the throw of the arms.

8. The combination with a traveling selector and denominational bars, of an array 35 of jacks moved *seriatim* by said selector, a transposition device between said bars and said jacks, said device comprising a set of nested bails, a single shaft for said bails, an arm whereby each bail moves its bar, stops 40 for limiting the throw of the arms to position the bars, a second arm for each bail, and a link connecting each jack to its arm.

9. The combination with a traveling selector and denominational bars, of horizontal 45 jacks adapted to be moved by said selector, a shaft, transposition bails journaled on the shaft, an arm on each bail bearing against its bar, a second arm on each bail, and a link extending down from each 50 jack to its said second arm.

10. The combination with a traveling selector and denominational bars, of horizontal 55 jacks adapted to be moved by said selector, a shaft, transposition bails journaled on the shaft, an arm on each bail bearing against its bar, a second arm on each bail, a link extending down from each jack to its 60 said second arm, a pair of additional arms, and a hub for said pair journaled on said shaft, so that one arm of said pair is connected to one jack and the other arm of the pair is connected to one bar.

11. The combination with denominational 65 pin-bars and pin-setting linkages, of springs normally holding the bars out of alinement,

an arm bearing against each bar adapted to move it to carry its pins to setting position, a bail fast to said arm, a second arm fast to the bail, a typewriter carriage, a denomination-selector on said carriage, jacks moved 70 by said selector, and a connection from each jack to its said second arm.

12. The combination with denominational pin-bars and setting links normally out of alinement, of an arm for each bar to move 75 it into alinement, a shaft on which said arm is journaled, a denomination-selector, jacks moved thereby, a second set of arms on said shaft, individually connected to the first bars, and a rod for each jack connecting it 80 to its arm of the second set.

13. A combined typewriting and computing machine comprising a typewriter carriage, a denomination selector, a set of devices displaceable by said denomination selector, a set of computation bars whose denominational order is the reverse of that of 85 said displaceable devices, and a set of bell-crank arms to transmit movement from the displaceable devices to the computation bars; 90 said bell-crank arms comprising bails of various widths and nested in a manner to render the denominational order of one set of bell-crank arms the reverse of the order of the other set of bell-crank arms. 95

14. A combined typewriting and computing machine comprising a typewriter carriage at the upper portion of the machine, a set of devices displaceable *seriatim* by 100 said carriage and extending down therefrom, a set of forwardly extending computation bars of the reverse denominational order from said displaceable devices, and a set of bell-crank arms to transmit the movement 105 of the displaceable devices to the computation bars; said bell-crank arms comprising nested bails of various sizes arranged so that the order of one set of arms is the reverse of the order of the other set.

15. A combined typewriting and computing machine comprising a typewriter carriage at the upper portion of the machine, a set of devices displaceable *seriatim* by 110 said carriage and extending down therefrom, a set of forwardly extending computation bars of the reverse denominational order from said displaceable devices, and a set of bell-crank arms to transmit the movement 115 of the displaceable devices to the computation bars; said bell-crank arms comprising nested bails of various sizes arranged so that the order of one set of arms is the reverse of the order of the other set, and so that the set of arms operating the computation bars is substantially wider than the set operated by the 120 displaceable devices.

16. A combined typewriting and computing machine comprising a typewriter carriage, a denomination selector, a set of denomination jacks, a set of links extending 130

from said denomination jacks, a set of computing bars arranged in the reverse denominational order from the links, and a set of bell-cranks connecting said links to said bars, said bell-cranks comprising mainly bails of various widths nested in a manner to render the denominational order of one set of bell-cranks the reverse of the order of the other set of bell-cranks.

17. A combined typewriting and computing machine comprising a typewriter carriage, a denomination selector, a set of denomination jacks, a set of links extending from said denomination jacks, a set of computing bars arranged in the reverse denominational order from the links, and a set of bell-cranks connecting said links to said bars, said bell-cranks comprising mainly bails of various widths nested in a manner to render the denominational order of one set of bell-cranks the reverse of the order of the other set of bell-cranks, said bell-cranks so formed that the arms thereof which operate the computation bars are substantially farther apart than the arms thereof which are operated by the links.

18. A combined typewriting and computing machine comprising a typewriter carriage, a denomination selector, a set of denomination jacks, a set of links extending from said denomination jacks, a set of computation bars extending forwardly, the order of said computation bars being the reverse of the order of the links, and means in the form of a transposition device connecting the lower ends of said links to said bars; said transposition device comprising a set of nested bails, each having an arm extending to a computation bar and an arm extending to a link, said bails so nested that the denominational order of one set of arms is the reverse of the order of the other set of arms.

19. In a combined typewriting and computing machine, the combination of a typewriter carriage, a set of denomination-devices displaceable thereby, a set of computation-bars of the reverse denominational order from said displaceable devices, and a set of bell-cranks, mainly of bail form, and so formed and nested that one set of arms has the reverse denominational order from the other set of arms, said bell-cranks communicating motion from said devices to said computation-bars.

20. In a combined typewriting and computing machine, the combination of a typewriter carriage, a set of denomination-devices displaceable thereby, a set of computation-bars of the reverse denominational order from said displaceable devices, a set of bell-cranks, mainly of bail form, and so formed and nested that one set of arms has the reverse denominational order from the

other set of arms, said bell-cranks communicating motion from said devices to said computation-bars, and means whereon said bell-cranks are mounted to be detachable as a unit from the machine.

21. In a combined typewriting and computing machine, the combination of a typewriter carriage, a set of denomination-devices displaceable thereby, a set of computation-bars of the reverse denominational order from said displaceable devices, a set of bell-cranks, mainly of bail form, and so formed and nested that one set of arms has the reverse denominational order from the other set of arms, said bell-cranks communicating motion from said devices to said computation-bars, and means whereon said bell-cranks are mounted to be detachable as a unit from the machine, said bell-cranks having open slots to be detachably engaged by said displaceable devices, and also having open slots for detachable engagement with said computation-bars.

22. In a combined typewriting and computing machine, the combination of a typewriter carriage, a set of denomination-devices displaceable thereby, a set of computation-bars of the reverse denominational order from said displaceable devices, a set of bell-cranks, mainly of bail form, and so formed and nested that one set of arms has the reverse denominational order from the other set of arms, said bell-cranks communicating motion from said devices to said computation-bars, and means whereon said bell-cranks are mounted to be detachable as a unit from the machine, said bell-cranks having open slots to be detachably engaged by said displaceable devices, and also having open slots for detachable engagement with said computation-bars, the bail portions of certain of said bell-cranks being of graduated sizes, and nested one within another, and extending in one direction from the arms which operate the computation-bars, and the bail portions of certain others of said bell-cranks being also of graduated sizes, and nested one within another, and extending in the opposite direction from certain of the arms which operate the computation-bars.

23. In a combined typewriting and computing machine, the combination of a typewriter carriage, a set of denomination-devices displaceable thereby, a set of computation-bars of the reverse denominational order from said displaceable devices, a set of bell-cranks, mainly of bail form, and so formed and nested that one set of arms has the reverse denominational order from the other set of arms, said bell-cranks communicating motion from said devices to said computation-bars, and means whereon said bell-cranks are mounted to be detachable as a unit from the machine, said bell-cranks hav-

- 6
- ing open slots to be detachably engaged by said displaceable devices, and also having open slots for detachable engagement with said computation-bars, the bail portions of certain of said bell-crank being of graduated sizes, and nested one within another, and extending in one direction from the arms which operate the computation-bars, and the bail portions of certain others of said bell-crank being also of graduated sizes, and nested one within another, and extending in the opposite direction from certain of the arms which operate the computation-bars, said nests of bails extending one alongside the other.
24. In a combined typewriting and computing machine, the combination of a typewriter carriage, denominational devices displaceable thereby and including a set of rods or the like, a set of computation-bars, and a set of bell-crank to communicate motion from said rods to said computation-bars,
- 5 10 15 20 25 30 35
- said set of bell-crank constituting a denominational transposition device.
25. In a combined typewriting and computing machine, the combination of a typewriter carriage, denominational devices displaceable thereby and including a set of rods or the like, a set of computation-bars, and a set of bell-crank to communicate motion from said rods to said computation-bars, said set of bell-crank constituting a denominational transposition device, each bell-crank consisting of a single movable member, and the bell-crank constructed mainly of bails of graduated sizes and nested and formed to render the denominational order of one set of bell-crank-arms the reverse of the denominational order of the other set of bell-crank-arms.
